SIDING

Fay J. Raftery, 14100 Brady, Redford Township,
Detroit 39, Mich., and James E. Raftery, 16759 Rouge-
way Drive, Livonia, Mich.

Filed June 2, 1961, Ser. No. 65,439

Term of patent 14 years

(Cl. D13—1)

The FIGURE is a fragmentary perspective view of a siding, an intermediate portion thereof being broken away to indicate indefinite length.

The design is characterized by a lower vertical portion of the siding being inclined with respect to an upper vertical portion of the siding, and an intermediate portion connecting said vertical portions, the intermediate portion constituting a horizontal groove.

The dominant features of our design reside in the portions shown in full lines and the top of the siding is shown fragmentarily for convenience of illustration only.

We claim:

The ornamental design for a siding, substantially as shown and described.
